US00D880716S

(12) **United States Design Patent** (10) **Patent No.:** **US D880,716 S**
Wersland et al. (45) **Date of Patent:** **** Apr. 7, 2020**

- (54) **PERCUSSIVE MASSAGE DEVICE**
(71) Applicant: **THERAGUN, LLC**, Santa Monica, CA (US)
(72) Inventors: **Jason Wersland**, Manhattan Beach, CA (US); **Benjamin Nazarian**, Beverly Hills, CA (US); **Jaime Sanchez Solana**, Los Angeles, CA (US); **Trent Hernandez**, Los Angeles, CA (US); **Rene Oehlerking**, Los Angeles, CA (US); **Dennis Matthew Puhalla**, Chicago, IL (US); **Jillian Tackaberry**, Chicago, IL (US); **Gary Paulsen**, Chicago, IL (US)
(73) Assignee: **THERAGUN, LLC**, Santa Monica, CA (US)
(**) Term: **15 Years**
(21) Appl. No.: **29/674,846**
(22) Filed: **Dec. 26, 2018**
(51) LOC (12) Cl. **28-03**
(52) U.S. Cl. **D24/215**
(58) **Field of Classification Search**
USPC ..... 601/15, 18, 19, 27, 28, 29, 30, 31, 32, 601/46, 47, 48, 52, 72, 99, 112, 113, 118, 601/135, 137, DIG. 12, DIG. 14, DIG. 15, 601/DIG. 16, DIG. 17; D24/200, 211, D24/212, 213, 214, 215; D8/14.1; 607/85
CPC .. A61H 23/0254; A61H 1/008; A61H 23/006; A61H 7/007

(57) **CLAIM**

The ornamental design for a percussive massage device, as shown and described.

DESCRIPTION

FIG. 1 is a top perspective view of a percussive massage device, showing our new design;

FIG. 2 is a right side elevational view;

FIG. 3 is a left side elevational view;

FIG. 4 is a front elevational view;

FIG. 5 is a rear elevational view;

FIG. 6 is a top plan view;

FIG. 7 is a bottom plan view; and,

FIG. 8 is a bottom perspective view.

The broken lines shown in the figures are for the purpose of illustrating portions of the percussive massage device that form no part of the claimed design.

1 Claim, 6 Drawing Sheets
